UNITED STATES PATENT OFFICE

130,125

DESIGN FOR A CHEESE SERVER OR ANALOGOUS ARTICLE

Carl Horix, Chicago, Ill.

Application May 9, 1941, Serial No. 100,859

Term of patent 14 years

To all whom it may concern:

Be it known that I, Carl Horix, a citizen of the United States, residing at Chicago, in the county of Cook and State of Illinois, have invented a new, original, and ornamental Design for a Cheese Server or Analogous Article, of which the following is a specification, reference being had to the accompanying drawing, forming a part thereof:

In the drawing:

Fig. 1 is a front perspective view of the cheese

server, consisting of a tray, a housing for a block of cheese, and a serving knife removably positioned on the side thereof, showing my design;

Fig. 2 is a front elevational view of the same, and

Fig. 3 is a top plan view thereof.

I claim:

The ornamental design for a cheese server or analogous article, as shown and described.

CARL HORIX.
